MASS SPECTROMETER

William H. Wells, Detroit, Mich., assignor to Bendix Aviation Corporation, Detroit, Mich., a corporation of Delaware

Application November 16, 1953, Serial No. 392,180

7 Claims. (Cl. 250—41.9)

This invention relates to mass spectrometers and more particularly to mass spectrometers for providing an enhanced resolution between ions of different mass.

In some mass spectrometers, a plurality of ions are formed from the molecules of different gases and vapors in an unknown mixture. After a considerable number of ions have been formed, a force is imposed upon the ions to accelerate the ions in a pulse from their place of retention. Since the ions of relatively light mass receive a greater acceleration than the ions of heavier mass during application of the force, the ions of light mass have a higher velocity than the ions of heavier mass at the time of removal of the force. As a result, the ions of relatively light mass travel through a particular distance before the ions of heavier mass. By measuring the relative times at which the ions of different mass are detected, the masses of the different gases in the unknown mixture can be determined.

Ideally, optimum indications would be obtained if all the ions of a particular mass reached a detector at substantially the same instant of time. This does not occur in mass spectrometers now in use for a number of reasons. One reason is that ions of a particular mass are located at different positions within their space of retention before a force is applied to accelerate the ions towards a detector. As a result, ions of the same mass may reach the detector at slightly different times. Furthermore, thermal and other energy in the ions imparts a random motion to the ions before the application of any force so that some ions of a given mass may be moving towards the detector at the time the force is imposed and other ions of the same mass may be moving away from the detector at that instant. Thus, the thermal and other energy in the ions also prevents all the ions of a particular mass from being simultaneously detected in mass spectrometers now in use.

This invention provides a mass spectrometer in which errors resulting from differences in the positioning and random motion of individual ions are minimized. The errors are minimized by disposing a detector at a predetermined distance from an ion source and by applying to the ions an accelerating force having a magnitude which increases in relation to time. The application of such a force causes an enhanced resolution to be obtained between the ions of different mass.

An object of this invention is to provide a mass spectrometer for distinguishing between ions of different mass by measuring the time required for the ions to travel through a predetermined distance.

Another object of the invention is to provide a mass spectrometer for obtaining an enhanced resolution between ions of different mass in comparison with the resolution obtained in spectrometers now in use.

A further object is to provide a mass spectrometer of the above character having a detector plate disposed at a particular distance from an ion source to improve the response characteristics of the spectrometer.

Still another object is to provide a mass spectrometer

2

of the above character for applying to the ions an accelerating force having a magnitude which increases in relation to time to enhance the resolution between ions of different mass.

5 A still further object is to provide a mass spectrometer of the above character for minimizing errors in resolution which result from the different positioning and random motion of individual ions before they are subjected to an accelerating force.

10 Another object is to provide methods of producing a relatively sharp separation between the ions of different mass and of determining the masses of the different ions.

Other objects and advantages will be apparent from a detailed description of the invention and from the appended drawings and claims.

In the drawings:

Figure 1 is a somewhat schematic diagram, partly in block form and partly in perspective, illustrating one embodiment of the invention.

20 Figure 2 is a somewhat schematic diagram of certain components shown in Figure 1 and further illustrates their operation.

Figures 3A and 3B show curves illustrating the relationship with respect to time of the voltages applied to certain of the members shown in Figure 1.

25 In one embodiment of the invention, a wedge-shaped filament 10 made from a suitable material such as tungsten is adapted to emit electrons when heated. An electrode 12 is disposed at a relatively short distance such as $\frac{1}{4}$ millimeter from the tip of the filament 10. The electrode 12 is provided with a vertical slot 14, the median position of which is at substantially the same horizontal level as the filament 10.

30 An electrode 16 is disposed in substantially parallel relationship to the electrode 12 and at a relatively short distance such as 2 millimeters from the electrode. The electrode 16 has a slot 18 corresponding substantially in shape and position to the slot 14. A collector 20 is disposed at a relatively great distance such as 10 centimeters from the electrode 16 and in substantially parallel relationship to the electrode.

35 A backing plate 22 is positioned between the electrode 16 and the collector 20 and in substantially perpendicular relationship to these members. The backing plate 22 is positioned at a relatively short distance such as 1 centimeter to the rear of an imaginary line extending from the tip of the filament 10 through the slots 14 and 18 to the collector 20. An electrode 24 is disposed in substantially parallel relationship to the backing plate and at a moderate distance such as 5 centimeters from the plate. The electrode 24 is positioned in front of the imaginary line disclosed above and is provided with a horizontal slot 26.

40 A pair of slats 28 made from a suitable insulating material extend from the top and bottom of the backing plate 22 and are suitably connected to the electrode 24 to form a compartment with these members. A horizontal slot 30 is provided in the bottom slat 28 at a position directly below the imaginary line disclosed above. A conduit 32 communicates at one end with the slot 30 and at the other end with a receptacle 34 adapted to hold the molecules of different gases in an unknown mixture.

45 A detector such as a collector 36 is positioned at a relatively great distance such as 8 centimeters from the electrode 24. The distance between the collector 36 and the electrode 24 should be substantially twice the distance between the imaginary line and the electrode 24 for reasons which will be disclosed in detail hereinafter. An indicator such as an oscilloscope 38 is connected to the collector 36 to indicate the relative times at which ions of different mass are detected.

A direct voltage of positive polarity is applied to the electrode 12 through a resistance 40 from a suitable power supply 42. The collectors 20 and 36 also have slightly positive voltage applied to them through suitable resistances 44 and 46, respectively, from the power supply 42. These voltages are applied to the collectors 20 and 36 so that the collectors will attract electrons secondarily emitted from them upon impingement of charged particles. The filament 10 and the backing plate 22 are connected to grounded resistances 48 and 50, respectively, and the electrodes 16 and 24 are directly grounded.

Negative pulses of voltage are applied to the filament 10 and the electrode 12 through coupling capacitances 52 and 54 from a suitable pulse forming circuit 56. The output terminal of a waveform generator 58 is connected to the backing plate 22 through a suitable coupling capacitance 60. The waveform generator 58 is adapted to introduce to the backing plate 22 a positive voltage pulse having an amplitude which increases in relation to time. For this purpose, the waveform generator 58 may include any one of a number of circuits, the construction and operation of which are known to persons skilled in the art. For example, the circuit disclosed in U. S. Patent No. 2,729,815, to Gilman B. Andrews et al. can be conveniently adapted to provide a voltage pulse having an increasing amplitude by superimposing a saw-tooth voltage upon a square wave voltage.

A trapezoidal waveform generator as fully disclosed on page 297 of "Waveforms," volume 19 of the Radiation Laboratory Series published by Massachusetts Institute of Technology, can also be used. The increase in the amplitude of the voltage pulse applied to the backing plate 22 need not necessarily be linear with respect to time but may be of any desired shape. For example, circuits disclosed on pages 301 to 312, inclusive, of the above-mentioned publication may be utilized as part of the waveform generator 58 to provide voltage pulses having amplitudes which increase hyperbolically or parabolically in relation to time.

As will be disclosed in detail hereinafter, the voltage pulses of increasing amplitude applied to the backing plate 22 occur at a later time than the pulses applied to the filament 10 and the electrode 12 from the pulse forming circuit 56. A voltage pulse is also applied to the oscilloscope 38 from the function generator 58 to initiate the horizontal sweep of the oscilloscope beam at substantially the same instant as the voltage pulses are applied to the backing plate 22.

In the steady state operation, the electrons emitted by the filament 10 are attracted to the electrode 12 because of the positive voltage on the electrode relative to the voltage on the filament. The electrons are decelerated in the region between the electrodes 12 and 16 since the electrode 16 is at substantially the same potential as the filament 10. This prevents electrons from travelling through the region between the backing plate 22 and the electrode 24 with sufficient energy to ionize molecules of gas and vapor introduced into the region from the receptacle 34.

Upon the imposition of negative pulses of voltage on the filament 10 and the electrode 12, the voltage on the electrode 12 becomes negative with respect to the voltage on the electrode 16. This causes electrons travelling through the slot 14 to be further accelerated in the region between the electrodes 12 and 16. Because of the acceleration imparted to the electrons in the region between the electrodes 12 and 16, the electrons travel into the region between the backing plate 22 and the electrode 24 with sufficient energy to ionize molecules of the gases and vapors in the region. Most of the ions which are produced have a unitary positive charge.

The ions which are produced by the electron stream are retained in the electron stream because of their opposite charges relative to that of the stream. The pulse forming circuit 56 is set to apply the pulses to the filament

10 and the electrode 12 for a particular period of time to allow a considerable number of ions to be produced for retention in the stream. When the pulses are cut off, the ions are available for easy withdrawal upon the application of a voltage pulse to the backing plate 22 from the waveform generator 58. The waveform generator 58 is set to apply the pulse to the backing plate 22 at a particular time after the pulses applied to the filament 10 and the electrode 12 are cut off.

Upon the application of voltage pulses to the backing plate 22 from the waveform generator 58, an electric field is produced between the plate and the electrode 24 to withdraw the ions towards the slot 26. The ions of light mass will have a greater acceleration imparted to them than the ions of heavier mass. This causes the ions of light mass to attain a greater velocity upon reaching the slot 26 than the velocity attained by the ions of heavier mass. After travelling through the slot 26 in the electrode 24, the ions travel to the collector 36 with substantially the same velocity as they had upon reaching the slot 26. This results from the fact that substantially no electric field is produced in the region between the electrode 24 and the collector 36 since the electrode is at ground potential and the collector is at a potential only slightly above ground. During their travel through the region or drift space between the electrode 24 and the collector 36, the ions become materially separated on the basis of their mass because of the differences in the velocities imparted to them on the basis of their mass. By measuring the relative times at which different groups of ions reach the collector 36, the masses of the ions in each group can be determined.

It has been found that errors in measurement result in spectrometers now in use because of the different positioning of individual ions in the ionization region. For example, as illustrated in Figure 2 an ion 100 of a given mass may be located spatially behind the imaginary line disclosed above and an ion 102 of the same mass may be located in front of the imaginary line. Since the ion 100 has to travel through a greater distance to the electrode 24 than the ion 102, the ion 100 is subjected to the electrical field between the backing plate 22 and the electrode 24 for a longer period than the ion 102. As a result the ion 100 attains a greater velocity upon reaching the slot 26 than does the ion 102. Even though the ion 100 will have a greater velocity than the ion 102, the ion 100 may arrive at the collector plate at a later time than the ion 102 because the drift space between the electrode 24 and the collector 36 may not be of a sufficient length to permit the ion 100 to catch up to the ion 102 which initially had an advantage in its spatial position. In this way, individual ions of a given mass may arrive at the collector plate before other ions of the same mass to cloud the measurements which are obtained.

Errors resulting from the different positioning of the ions can be minimized if the collector plate is placed at a proper distance from the electrode 24 to permit the ions behind the imaginary line to overtake the ions in front of the line. This distance has been found by analysis to be approximately twice the distance between the imaginary line and the electrode 24, as fully disclosed in co-pending application Serial No. 251,352 filed October 15, 1951, by me and William C. Wiley. By placing the collector 36 at this distance from the electrode 24, optimum focusing is provided to compensate for the different positioning of individual ions of a given mass.

As previously disclosed, errors in measurement also result in spectrometers now in use from the random motion imparted to the ions by the thermal and other energy of the ions before the application of any external forces. For example as illustrated in Figure 2, an ion 104 of a given mass may have an initial velocity V_0 towards the backing plate 22 and an ion 106 of the same mass may have an initial velocity of V_0 towards the electrode 24. Obviously, the ion 106 will reach the col-

5

lector 36 before the ion 104 upon application of a pulse to the backing 22. This is true because the ion 104 will travel towards the backing plate a certain distance "d" before it is stopped by the electrical field. Then the ion 104 will reverse its direction of flight towards the electrode 24.

When the ion 104 reaches its initial starting position after having traveled through the distance "d" in the direction of the electrode 24 it will acquire a velocity V_0 which is the same as the initial velocity V_0 of the ion 106. Therefore, the ion 104 will attain the same velocity that the ion 106 had attained upon reaching the electrode 24. Since the ion 104 travels from the electrode 26 to the collector 36 at substantially the same velocity as the ion 106, the ion 104 can never overtake the ion 106 which had an initial velocity V_0 towards the electrode 24. As a result, the ion 106 will reach the collector 36 before the ion 104. In this way, individual ions of a given mass may arrive at the collector at different times and affect the sharpness and accuracy of the measurements obtained.

If the voltage pulses applied to the backing plate 22 have a constant amplitude such as +300 volts, and the distance between the backing plate and the electrode 24 is 5 centimeters, the voltage gradient between the plate and the electrode will remain constant at -60 volts per centimeter, during the period of application of the pulses. With such a constant voltage gradient, ions having different thermal and other energy such as the ion 104 and the ion 106 can never arrive at the collector 36 at the same time for the reasons disclosed above.

This invention provides apparatus for minimizing the errors resulting from thermal and other energy in the ions. As previously disclosed, the voltage pulses applied to the backing plate 22 from the waveform generator 58 have an amplitude which increases in a predetermined manner with respect to time. For example, the voltage pulses applied may have an amplitude which increases in a parabolic curve from an initial value of +300 volts to a value of +450 volts at the end of the pulse. Such a voltage pulse is illustrated in Figure 3A. With the application of such a pulse, the voltage gradient between the backing plate 22 and the electrode 24 will increase parabolically in a negative direction from -60 volts per centimeter to -90 volts per centimeter as shown in Figure 3B.

Since the voltage gradient increases in a negative direction with respect to time, individual ions of a given mass will be subjected to different amounts of force depending upon the time at which the ions reach the electrode 24. For example, the ion 106 may reach the electrode 24 at point 108 of the voltage gradient curve and the ion 104 may reach the electrode at a later time such as point 110 of the voltage gradient curve. Since the voltage gradient at point 110 is higher than the gradient at point 108, a greater acceleration will be imparted to the ion 104 than to the ion 106. As a result, the ion 104 will pass from the slot 26 in the electrode 24 into the drift space between the electrode and the collector 36, with a greater velocity than the velocity of the ion 106. If the greater velocity imparted to the ion 104 is of a sufficient magnitude, the ion 104 will overtake the ion 106 at substantially the time that the ion 106 arrives at the collector 36. Therefore the ion 104 and the ion 106 will impinge upon the collector 36 at substantially the same time to provide sharp and accurate measurements.

The mass spectrometer disclosed above provides an enhanced resolution between ions of different mass in comparison with the resolution obtained in spectrometers now in use. The enhanced resolution is obtained by the disposition of the detector at a particular distance from the starting point of the ions to minimize the errors resulting from the different spacial positioning of the ions in their place of retention before application of an accelerating force. The resolution is further enhanced by applying an accelerating field which changes with respect

6

to time to impart different velocities to individual ions of a given mass so as to minimize any errors resulting from the thermal and other energies in the ions.

It should be recognized that the accelerating force may be varied in other ways than by increasing the amplitude of the voltage pulses applied to the backing plate 22. For example, a voltage pulse having a constant amplitude may be applied to the backing plate 22 and a voltage pulse having a decreasing amplitude may be applied to the electrode 24. Furthermore, the curve of change in the amplitude of the pulse can be varied in any desired manner to provide enhanced resolutions over a wide range of different masses. It should also be recognized that an increasing accelerating force to compensate for thermal and other energies of ions may be utilized in mass spectrometers having a plurality of accelerating regions such as is fully disclosed in U. S. Patent No. 2,685,035 to William C. Wiley.

Although this invention has been disclosed and illustrated with reference to particular applications, the principles involved are susceptible of numerous other applications which will be apparent to persons skilled in the art. The invention is, therefore, to be limited only as indicated by the scope of the appended claims.

1. A mass spectrometer, including, a backing plate, an electrode disposed a particular distance from the backing plate, means for providing a plurality of ions in the region between the backing plate and the electrode, means for applying between the backing plate and the electrode an electric field having an intensity which increases with respect to time to produce a movement of the ions past the electrode and to produce a separation of the ions on the basis of their mass, a detector disposed beyond the electrode at substantially the position of optimum focus of the ions, and means for indicating the relative times at which ions of different mass are detected.

2. A mass spectrometer, including, means for providing a first region, means for providing a plurality of ions in the region, means for imposing in the region an accelerating force having a magnitude which increases with respect to time to produce a movement of the ions past the end of the region and to produce a separation of the ions on the basis of their mass, a detector disposed past the end of the first region at substantially the position of optimum focus of the ions, and means for indicating the relative times at which ions of different mass are detected.

3. A mass spectrometer, including, a backing plate, an electrode disposed at a particular distance from the backing plate, means for providing a plurality of ions in the region between the backing plate and the electrode and for retaining the ions in the region, an electrical circuit for producing between the plate and the electrode an electrical field having an intensity which increases in a particular relationship with respect to time to produce a movement of the ions past the electrode and to produce a separation of the ions on the basis of their mass, the electric field being operative to impart different velocities to individual ions of any given mass to compensate for any differences in the initial energies possessed by the ions, a detector disposed at substantially the focal position of the ions of each mass, and means for indicating the relative times at which the ions of different masses are detected.

4. A mass spectrometer, including, means for providing a first region, means for providing a plurality of ions in the region, means for applying in the region a force having a non-linear relationship through the region to produce a movement of the ions past the end of the region and to produce a separation of the ions on the basis of their mass, means disposed past the end of the first region at substantially the position of optimum focus of the ions to detect the ions, and means for indicating the relative times at which the ions of different mass are detected.

5. A mass spectrometer, including, a first electrode, a second electrode disposed at a particular distance from the first electrode, means for providing a plurality of ions in the region between the first and second electrodes, means for applying between the first and second electrodes an electrical field of varying intensity to produce a movement of the ions past the second electrode and to produce a separation of the ions on the basis of their mass, a detector disposed at a particular distance from the second electrode, and means for indicating the relative times at which the ions of different masses are detected.

6. A mass spectrometer, including, a first electrode, a second electrode disposed at a particular distance from the first electrode, means for providing a plurality of ions in the region between the first and second electrodes, means for applying between the first and second electrodes an electric field having an intensity which varies in a linear relationship with respect to time to produce a movement of the ions past the second electrode and to produce a separation of the ions on the basis of their mass, means disposed at a particular distance from the second electrode to detect the ions, and means for indicating the relative times at which the ions of different mass are detected.

15

20

7. A mass spectrometer, including, a first electrode, a second electrode disposed at a particular distance from the first electrode, means for providing a plurality of ions in the region between the first and second electrodes, 5 means for applying between the first and second electrodes an electric field having an intensity which varies in a particular non-linear relationship with respect to time to produce a movement of the ions past the second electrode and to produce a separation of the ions on the basis of their mass, a detector disposed at substantially the position of optimum focus of the ions, and means for indicating the relative times at which the ions of different mass are detected.
